UNITED STATES PATENT OFFICE

WALTER F. WEGNER, OF EAST WILLIAMSON, NEW YORK, ASSIGNOR TO FRUIT BELT PRESERVING COMPANY, OF EAST WILLIAMSON, NEW YORK, A CORPORATION OF NEW YORK

METHOD OF COOLING CANNED GOODS AND APPARATUS USED IN SUCH METHOD

Application filed December 10, 1927. Serial No. 239,249.

The present invention relates to a method of cooling canned goods and to an apparatus used in such method, and an object of the invention is to provide for cooling effectively 5 a number of cans in bulk.

To these and other ends, the invention consists in the method hereinafter set forth as well as the apparatus hereinafter described: the particular features being pointed out in 10 the appended claims.

In the drawings:

Fig. 1 is a longitudinal sectional view through the apparatus;

Fig. 2 is a fragmentary plan view of the 15 apparatus; and

Fig. 3 is a transverse section through the apparatus.

Prior to this invention the cooling of canned goods in bulk has been accomplished 20 in a number of ways, one of which consists in passing the canned goods in open-work baskets or containers through a tank or vat of cold water. This method has resulted in the cooling of those cans on the 25 outermost portions of the basket in which the cans are arranged, but those cans arranged at the center of the basket maintain a hot condition because the cold water is heated before it reaches such cans. In this invention, the cold water is caused to circulate upwardly through the bottom of the basket from 30 the bottom of the tank, and if the cans are moved through the tank they are subjected to two currents, one horizontally or in the 35 direction of the length of the tank, due to the movement of the basket in the tank, and the other vertically from the bottom of the tank.

In carrying out this invention, the tank 1 is an elongated structure similar to that now 40 in use and through this tank the canned goods 2 are moved in the direction of the length of the tank. These canned goods are arranged in bulk, in this instance, in an open work basket 3 being positioned in the basket on 45 their ends and in different layers, the bottoms of the cans of one layer resting on the upper ends of the cans of the layer next beneath. The baskets may be moved through the tank or receptacle 1 in any suitable manner. In this instance, their bails 4 are sus-

pended from hooks 5 on a wheeled carrier 6 travelling on a trackway 7 extending longitudinally of the tank 1. The movement of the basket through the carrier creates a current longitudinally of the tank past the 55 canned goods.

With the end in view of producing an upward current between the cans, one or more air pipes 8 may be provided extending longitudinally of the tank and each provided with 60 a longitudinal series of jet openings. These pipes, in this instance, are located near the middle of the tank and near the vertical center of the basket. The issuing of cold air from these jet openings 9 creates a current 65 upwardly through the bottoms of the baskets and between the cans therein, the water then flowing outwardly toward the sides of the receptacles and then downwardly to the bottom of the tank, as indicated by 70 arrows 10, Fig. 3.

It will thus be seen that there has been provided an effective means for cooling canned goods in bulk. The canned goods while arranged in an open work basket submerged 75 in a liquid bath are subjected to a cold water current passing upwardly through the open work basket from the bottom thereof and between the cans at the center of the open work basket. At the same time the open work 80 basket with the cans therein is moved bodily through an elongated tank so as to create a current about the cans, thus preventing discoloring of the product.

This method eliminates the polishing of 85 the cans before they are shipped and the upward current prevents the formation of the usual film or dirt coating which collects on the cans under the old methods.

What I claim as my invention and desire 90 to secure by Letters Patent is:

1. A method of cooling canned goods in bulk which consists of moving an openwork basket bodily through a body of cold liquid with the cans submerged in such liquid, and 95 creating a current upwardly between the cans from the bottom of the receptacle.

2. A method of cooling canned goods in bulk which consists in moving horizontally through a liquid body an openwork basket 100

with the cans arranged therein on their ends, and projecting upwardly air jets into the liquid body beneath the basket to create an upward current between the cans in the basket.

5 3. An apparatus for cooling canned goods in bulk comprising a tank containing the cooling liquid, an openwork basket containing the cans in bulk, and means for creating an upward current of the liquid in the tank through the bottom of said openwork receptacle.

10 4. An apparatus for cooling canned goods in bulk comprising an elongated tank for containing the cooling liquid, an openwork basket for containing the canned goods, means guiding said basket in a submerged condition longitudinally of the tank, and an air pipe extending longitudinally of the tank near the middle of the tank and beneath the basket, said pipe having jet openings discharging upwardly.
